UNITED STATES PATENT OFFICE.

HOMER MONROE MACE, OF CATSKILL, NEW YORK.

RAIL-FASTENER.

No. 798,812.

Specification of Letters Patent.

Patented Sept. 5, 1905.

Application filed February 28, 1905. Serial No. 247,678.

To all whom it may concern:

Be it known that I, HOMER MONROE MACE, a citizen of the United States, and a resident of Catskill, in the county of Greene and State 5 of New York, have invented a new and Improved Rail-Fastener, of which the following is a full, clear, and exact description.

The object of the invention is to provide a fastening device to be used in connection with 10 railway-rails for the purpose of holding them firmly to their ties, which device will prevent the rails from spreading and tilting and will also reduce to a minimum their tendency to creep.

15 The invention consists in the novel construction and combination of the several parts, as will be hereinafter fully set forth, and pointed out in the claims.

Reference is to be had to the accompanying 20 drawings, forming a part of this specification, in which similar characters of reference indicate corresponding parts in all the figures.

Figure 1 is a perspective view of a portion of a railway-track and the improved fastening device applied to the rails. Fig. 2 is a longitudinal section through a portion of a railway-tie and a transverse section through a rail and fastening device for the same, the section being taken practically on the line 2 2 of Fig. 3. 25 Fig. 3 is a vertical transverse section through a railway-sleeper and the fastening device for a rail and a side elevation of a portion of a rail held to the sleeper by the fastening device, the section being taken substantially on 30 the line 3 3 of Fig. 2; and Fig. 4 is a side elevation of a portion of a railway-tie and a slightly-modified form of fastening device and a transverse section through a rail secured by the said fastening device.

40 A represents the ties or sleepers of a railway-track and B the rails held to various of the ties by spikes 10, and C represents the improved fastening device employed at intervals in the path of the rails to securely fasten them 45 to the ties.

In the construction of the fastening device C three primary elements are employed—namely, a bed-plate c, a locking-plate c', and clip-bolts c". The bed-plate c is of substantially the same width as that of the tie and of sufficient length to extend beyond both sides of the rail B it is adapted to support. At the inner end of the bed-plate a transverse rib 10^a is formed, and at the outer end 55 portion of the said bed-plate an inwardly-extending and more or less upwardly-inclined

fin 11 is produced, and the space 12 between the base of the bed-plate and the under side of the fin 11 is such as to snugly receive the outer flange 13 of a rail B, as is shown in 60 Figs. 1 and 2, and between the outer end of the base of a bed-plate and its fin 11 an aperture 15 is made, through which a spike 16 is driven into the tie A. The locking-plate c' is made wider at its inner end than 65 the width of the base of the bed-plate c, as is shown in Fig. 1, and is provided at said end with a recess 17, which snugly receives the rib 10^a of the bed-plate, and at the rear projecting side portion of the locking-plate 70 apertures 18 are made for a purpose to be herein-after described. In the further construction of the locking-plate c' an upwardly-inclined lip 19 is formed at its outer end of a width corresponding to that of the bed-plate c, and 75 where the lip 19 connects with the body of the locking-plate a transverse shoulder 20 is formed on its under face. When a locking-plate is placed in position upon a bed-plate, which occurs after the outer flange of a rail 80 has been fitted in the space 12 on the bed-plate c, the recess 17 of the locking-plate is made to receive the rib 10 of the bed-plate and the under inclined face of the lip 19 is made to bear upon the upper face of the inner 85 flange on the rail, the outer edge of the lip being brought firmly against the web of the rail, as is shown in Fig. 2, while the shoulder 20 of the locking-plate c' bears firmly against the longitudinal edge of the said flange, and then 90 the locking-plate is firmly secured to the tie in a removable manner. The locking-plate c' when placed in position fits so tightly to the bed-plate c and rail B as to effectually prevent the rail from creeping or moving in any 95 direction.

The locking-plate c' is locked in position by means of the clip-bolts c", which are passed through the apertures 18 in the locking-plate and engage with opposite sides of the tie A. 100 The upper ends of the clip-bolts c" are threaded and extend beyond the upper face of the locking-plate, while the lower ends of the clip-bolts are made more or less L-shaped, and their terminals are sharpened, as is shown at 105 21 in Fig. 3. In connection with the clip-bolts c" lock-nuts 22 are employed, screwed upon the upper ends of the said clip-bolts, and when the lock-nuts 22 are tightened the points 21 at the foot portions of the clip-bolts are 110 drawn up and embedded in the bottom portion of the tie, as is also shown in Fig. 3. In

this manner the locking-plate c' is firmly held in position relative to the bed-plate and the rail, and the bed-plate at its inner end portion is firmly secured to the tie, and whenever it is necessary to remove the locking-plate c' it can be done by removing the nuts 22 from the clip-bolts and lifting the locking-plate from the bed-plate.

In Fig. 4 I have illustrated a slight modification with reference to the construction of

- 10 the bed-plate, in that a vertical member 23 is carried upward from the fin 11, which vertical member engages with the web of the rail B and extends to the under face of its tread.
- 15 This construction of the bed-plate is especially adapted for use at the outer-rail so as to withstand in a positive manner any outward movement of said rail, especially on a curve.
- 20 Having thus described my invention, I claim as new and desire to secure by Letters Patent—
  1. A rail-fastener, consisting of a bed-plate having a fin extending upwardly from its upper face, forming a cavity for the reception 25 of the flange of a rail and provided with a rib at its opposite end, a locking-plate having one end adapted for engagement with the flange of a rail and the opposite end recessed to receive the rib of the bed-plate, and clamps arranged to hold the locking-plate in position on the bed-plate, and the two said parts in firm engagement with a tie.
  - 30 2. A rail-fastener, consisting of a bed-plate

having a fin extending inwardly from the upper face of one end portion and provided with 35 a transverse rib at the opposite end, a locking-plate fitted to that portion of the bed-plate carrying the rib, one end of the locking-plate being adapted for engagement with the flange of a rail, and clip-bolts passed through the 40 locking-plate, being arranged for engagement with the under face of a tie.

3. A rail-fastener, consisting of a bed-plate having a fin extending upwardly and inwardly from its outer end portion, forming a space 45 to receive the flange on a rail, the inner end of the said bed-plate being provided with a transverse rib, a locking-plate having a recess at its inner end to receive the said rib, the outer end of the locking-plate being shouldered at its under face and inwardly beveled to fit to the flange of a rail, and clip-bolts passed through the said locking-plate, which 50 clip-bolts have their lower ends L-shaped and their lower terminals pointed to enter the under face of a tie, and lock-nuts adapted to the upper end portions of the said clip-bolts, all for the purpose specified.

In testimony whereof I have signed my name to this specification in the presence of two sub- 55 scribing witnesses.

HOMER MONROE MACE.
